UNITED STATES PATENT OFFICE.

JOHN H. FELTHOUSEN, OF YORK, PENNSYLVANIA.

TURBINE.

1,433,066

Specification of Letters Patent. Patented May 16, 1916.

Application filed September 2, 1914. Serial No. 860,081.

To all whom it may concern:

Be it known that I, JOHN H. FELTHOUSEN, a citizen of the United States, residing at York, in the county of York and State of Pennsylvania, have invented new and useful Improvements in Turbines, of which the following is a specification:

This invention relates to turbines, and the primary object of the same is to provide means for automatically relieving accumulated water pressure from the top or one side of a runner and thereby materially reducing the friction on the running parts and the end or the down thrust on the bearings and consequently enhancing the running and power qualifications of turbines to a considerable extent.

A further object of the invention is to dispense with the use of exterior drain or relief pipes to clear the runner of accumulated water and in lieu thereof to provide means located interiorly of the turbine structure for accomplishing the same result without interfering with the requisite and desired operation of the runner and gates and also facilitating the installation of turbine organizations and at the same time causing the turbine to automatically preserve itself in the best running condition.

With the foregoing and other objects and advantages in view the invention consists in the preferred construction and arrangement of parts hereinafter more fully described and claimed and subject to such changes in proportions, dimensions and minor details as are contemplated by the scope of the invention.

In the drawings: Figure 1 is a longitudinal section when the turbine is horizontal, or a vertical section when the turbine is vertical. Fig. 2 is a similar view of the turbine installed in concrete or analogous setting and embodying a concrete scroll and draft tube. Fig. 3 is a side elevation of the main components of the turbine removed from the scroll and remaining mechanism and having the runner and its shaft withdrawn therefrom. Fig. 4 is a detail perspective view of the intermediate annular inclosure embodying hollow diffusers with which the gates co-operate, the inclosure being shown in inverted position. Figs. 5 and 6 are detail perspective views respectively of the top and bottom annular plates or ring frame members. Fig. 7 is a diagrammatic view, partially in top plan and sec-

tion, showing the hollow diffusers in the intermediate annular inclosure shown by Fig. 4, taken in the plane of the line A—A.

The construction and arrangement of the several parts are essentially the same in Figs. 1 and 2 except such changes as are necessary in the supporting elements to adapt the bed or pedestal supported structure, as shown by Fig. 1, to the concrete base or bed, scroll and draft tube as shown by Fig. 2. The turbine as usual embodies a runner 5 with blades 6 and the usual shaft 7 constituting the primal power medium or driving essentials for the power mechanism, the shaft 7 being supported by a thrust bearing 8 of well known form, as shown by Fig. 2, and may extend to and co-operate with a generator 9, also well understood in the art. The inclosure 10 of a guide bearing 11 bearing 10 has an intermediate flange 11 bearing 11 on and secured to the cylindrical body 12 by bolts 14. On the outer side of the inner cylindrical body 12 of the annular plate or ring 13 a gate shifting ring 15 is mounted, and co-operating therewith is a walking beam 16 adapted to be actuated in the usual manner to control the position of the gates and thereby regulate the inflow of the water to the runner as may be found necessary or desirable to conform to existing contingencies or to modify the speed of the runner. The top annular cover plate or ring 13 is formed with a chamber 17 intersected at intervals by radial ribs 18 which are inclined toward the center of the plate or ring or are reduced in vertical extent toward the center of the turbine so as to give ample clearance to the coupling head 19 to which the runner 5 is attached and also permit the more ready outthrowing of the water from the space 20 above the turbine by the centrifugal action of the latter into the chamber 17 of the plate 13 as will be more fully hereinafter explained. The outer side wall 21 of the plate 13 is slightly inclined inwardly and downwardly and at intervals between the ribs 18 has elongated outlet ports or openings 22 formed therein, and above the said side wall the plate 13 has an outwardly projecting peripheral flange 23.

Below the plate or frame 13 is an annular bottom plate or ring frame 24, as shown in detail by Fig. 6, and formed with an outwardly projecting upper portion or what may be termed a top rim 25 from which an inner extension 26 projects downwardly and

inwardly, as clearly shown by Fig. 6. The bottom plate 24 has a flange 27 which is connected to the parts 25 and 26 of the upper wall by radial ribs or partitions 30, said bottom plate being also formed with a chamber 29 intersected at intervals or divided by the said radial ribs or partitions 30, the chamber 29 being fully open between the ribs or partitions 30 to the interior of the draft tube a short distance above the draft tube flange 28^a, as clearly shown in Fig. 1. The inner wall 31 of the bottom plate 24 is unbroken by inward projections and is inclined inwardly in the same plane as the inner surface of the draft tube 28 so as to provide for an unobstructed clearance and outflow of the water after engaging the blades 6 of the runner through the said draft tube. The outer side wall 32 of the bottom plate or frame 24 is formed with a plurality of inlet ports or openings 33 between the ribs or partitions 30. The annular plates or ring frames 13 and 24 are both engaged by an outer component or inclosing annular frame 34, shown in inverted position by Fig. 3, and directly engaging the scroll 35, as shown by Fig. 1, and provided with a plurality of inlet openings 36 intersected by diffusers 37. The flange 23 of the top plate or frame 13 extends over a portion of the top of the intermediate inclosure 34, see Figs. 1, 4 and 7, and is secured to the inclosure by suitable bolts, the top portion of the inclosure being formed with an outwardly projecting peripheral flange 37^a which in turn is secured by suitable bolts to the upper inner portion of the scroll. The lower part of the intermediate inclosing frame or component 34 is secured to an offset 38 extending from the inner portion of the scroll, or the same may be a part of the base support for the turbine. It will be seen that the openings 36 gradually converge inwardly and coincide with the bottom and top portions respectively of the plates or frames 13 and 24, and the gates 41 are so shaped as to regularly continue the openings at a gradual downward angle of inclination in a curved plane without obstruction, and, moreover, the connecting webs 39 of the runner blades 6 move in an annular seat 40 in the upper inner portion of the plate or frame 24 flush with the adjacent portion of the extension 26 and the top of the said frame or plate 24. It will therefore be seen that the space between the bottom of the frame or plate 13 and the top of the frame or plate 24 forms a part of the passage for the water coming in from the scroll through the openings or main inlets 36 between the diffusers 37, the water striking the blades 6 of the runner to the best advantage and without obstruction, so that the greatest possible efficiency of the water may be obtained in its action on the runner.

The diffusers 37 are disposed at an angle or are tangential so as to cause the water to have an angular direction relatively to the gates 41, said gates being located between the planes of the bottom of the top frame or plate 13 and the top of the bottom plate or frame 24, and having shafts 42 projecting upwardly through the divided chamber 17 and also downwardly through the divided chamber 29 respectively of the top plate or frame 13 and the bottom plate or frame 24. The lower ends of the gate shafts 42 are held in suitable bearings in the bottom of the rim 25 of the plate or frame 24 and the upper parts of these shafts extend above the top portion of the plate or frame 13 and have crank arms 43 secured thereto and to suitable pins or studs 44 mounted in any preferred manner in an outstanding flange 45 at the base of the shifting ring 15 and whereby all of the gates may be uniformly opened and closed or moved to regulate the inflow of the water to the runner from the scroll. At the points where the shafts 42 extend through the bottom of the top plate or frame 13 and the top of the bottom plate or frame 24, water-tight bearings or packings will be introduced to prevent leakage at said points of the water into the chambers 17 and 29, but the upper and lower portions of the shafts 42 are water-lubricated and pass through tubes 46 which are fixed at their upper and lower ends and have intermediate slots or openings 47 exposing the intermediate portions of the upper and lower parts of the shafts to the water in the chambers 17 and 29, with obvious advantages in the movement of the said shafts. The shafts 42 are so mounted and connected to the mechanism with which they cooperate that vibrations of the gates will be absorbed and therefore will not affect the power transmission mechanism or the mechanism which the turbine is adapted to actuate.

At the upper and lower portions of the inner side of the intermediate inclosing frame or component 34, annular channels 48 and 49 are formed and divided by partitions 50 and 51, the said channels respectively standing opposite the outlet openings 22 of the top plate or frame 13 and the inlet openings or ports 33 of the bottom plate or frame 24. The annular channels 48 and 49 are also located above and below the diffusers 37, and as clearly shown by Fig. 7 the said diffusers are formed hollow, as at 51^a, and have their upper and lower portions respectively communicating with the lower portion of the channel 48 and the upper portion of the channel 49. In other words, the diffusers serve as ducts for setting up communication between the upper divided chamber 17 and the lower divided chamber 29 of the top plate 13 and bottom plate 24 in addition to their function of diffusing the

incoming water relatively to the gates 41 in accordance with the position of the said gates between the diffusers.

In the adaptation of the improvements as shown by Fig. 2, the runner 3 has a different type of blade 33, all of the blades depending below the bottom plate or frame 51, the latter being channelled or hollow as in the form shown by Fig. 1 with the exception that there is no outlet into the draft tube. The top frame or plate is essentially the same as that shown by Fig. 1 and the same reference character is applied thereto. The intermediate frame or including component is also practically of the same formation except such minor changes as to adapt it for association with the concrete scroll 53. The intermediate including frame or component as shown by Fig. 2 has the diffusers 37 mounted therein, and a communication between the upper terminals of the diffusers and the chamber 17 of the top plate or frame is established through the medium of a chamber 56 over the diffusers and in communication with the said chamber 17 through the inner side wall of the intermediate enclosure 31. The lower portions of the diffusers are connected by pipes or ducts 57 to downwardly extending ducts or outlets 58 formed in the concrete 59 and having outlet in the draft tube 60, produced in the present instance by suitable building the concrete in which also the scroll 53 is formed. It will therefore be seen that the essential features of the invention are the same in Fig. 2 as in Fig. 1 with the exception of such detail changes as are necessary to adapt the application of the several components to the concrete structure and as above explained.

The water around the top portion of the runner or between the main body of the runner and the lower portion of the top plate or frame passes into the space above the runner at the joint between the runner and the said frame owing to the intense pressure of the incoming water and the resistance set up, and if there were no relief for the accumulated water above the runner it is obvious that the pressure would soon become considerable, particularly in view of the rotation of the runner, and material resistance would be set up to the desired free action of the runner and greater wearing strain would be imposed upon the bearings. It has been the custom to use external pipes or drain ducts to relieve the space above the runner of the accumulated water, but this has not been altogether efficient or practicable, and hence the improvements have been devised to overcome the disadvantages incident to drainage structures for the purpose specified as heretofore employed and to effect an automatic relief. In the turbine embodying the features of improve-

ment as hereinbefore explained, the water accumulating in the space above the runner is given a centrifugal action and is continually thrown outwardly toward the outer portion of the partitioned or divided chamber 17 and passes through the outlets or ports 22 and then into the channel 48 and from the latter downwardly through the diffusers to the lower channel 49, in the constriction shown by Fig. 4, and from the said lower channel 49 the water then passes into the chamber 29 of the lower plate or frame, through the ports 33, and then passes out into the interior of the turbine below the runner a short distance above the draft tube.

Practically the same operation ensues in the construction shown by Fig. 2 with the exception that the water passes out through the ducts 57 and 58 from the lower portions of the diffusers and by means of this automatic relief of the water pressure the turbine organization as a whole is rendered more durable as well as effective in operation and the expense incident to installation is reduced, as the absence of exterior pipes for draining the space above the turbine and effecting the same operation automatically within the turbine renders the disposal or placement of the turbine organization as a whole much more convenient and effective.

What is claimed is:

1. A turbine installation comprising a casing, a runner and shaft therefor mounted in the casing, means for supplying the runner with water, the casing embodying a chambered structure around the shaft adjacent to the runner, and means embodied and inclosed within the turbine casing for effecting an automatic release of accumulated water from the said chambered structure.

2. A turbine installation comprising a casing, a runner and shaft therefor, the casing embodying a chambered structure around the shaft adjacent to the runner, means for supplying the runner with water, a draft tube with which the runner operates to carry off the water therefrom, and means within the casing for automatically effecting a release of the accumulated water from the chambered structure into the draft tube.

3. A turbine installation comprising a casing, a runner and shaft, a draft tube below the runner, the casing embodying a chambered structure adjacent to the upper portion of the runner and connected to the draft tube below the runner, means for supplying water to the runner, the casing also having opposed annular frames spaced from each other, and an intermediate annular enclosure frame having separated annular enclosures open to the outer portions of the chambered structure and also having open-

- ings therethrough between the channels with tubular diffusers and gates between the latter to control the supply of water to the runner from the water supplying means, 5 the tubular diffusers communicating with the channels of the intermediate frame whereby the water accumulating in the chambered structure may be automatically drained into the draft tube.
- 10 4. A turbine installation comprising a casing, a runner and shaft, a draft tube below the runner, the casing embodying a chambered structure adjacent to the upper portion of the runner and connected to the 15 draft tube below the runner, means for supplying water to the runner, the casing also having opposed annular frames spaced from each other, an intermediate annular frame having separated annular channels open to the outer portions of the chambered structure of the said opposed frames, the intermediate frame having openings therethrough between the channels with tubular diffusers therein, gates coöperating with 20 and between the diffusers and the said opposed frames to control the supply of water to the runner from the supply means, the gates having shafts projecting therefrom extending through the chambered structure, 25 and tubes fixed in the chambered structure and through which the gate shafts movably extend, said tubes having openings therein to water-lubricate the gate shafts.
- 30 5. A turbine installation comprising a casing, a runner and shaft therefor, a draft tube for egress of the water from the runner, water supply means for the runner, the casing embodying a chambered structure around the point of engagement of the shaft 35 with the runner and also adjacent to the point of engagement of the periphery of the runner with the casing for receiving accumulated water, the water being thrown outwardly from the shaft into the outer portion of the chamber, and means for automatically relieving the chamber of water 40 accumulated therein.
- 45 6. A turbine installation comprising a casing, a runner and shaft therefor, a draft tube, water supply means for the runner, the casing embodying a chambered structure around the point of engagement of the 50
- shaft with the runner and extending outwardly over the point of running engagement of the runner with the casing, the water being thrown outwardly from the shaft into the outer portion of the chamber, and means for relieving the accumulated water from the outer portion of the chamber and draining the said water into the draft tube, the means for relieving the accumulated water from the chamber being wholly inclosed within the casing. 55
7. A turbine installation comprising a casing, a runner, a draft tube, water supply means for the runner, said casing embodying a chambered structure at one end of the runner, and drain devices adjacent to the runner and between the same and the supply means and in communication with the draft tube for automatically relieving the said chambered structure and the adjacent portion of the runner of accumulated water. 60
8. A turbine installation comprising a casing, a runner therein, a draft tube, water supply means for the runner, the casing embodying a chambered structure located at one end of the runner and extending outwardly beyond said runner to receive water accumulating adjacent to the runner, the water being centrifugally thrown outwardly in the chambered structure by the runner, and drain devices within the casing between the outer portion of the chambered structure and the draft tube for automatically relieving said chambered structure of accumulated water. 65
9. A turbine installation comprising a casing, a runner therein, a draft tube, water supply means for the runner, the casing having a chambered structure therein extending outwardly beyond the periphery of and adjacent to the runner, and drain devices within the casing between the outer portion of the chambered structure and the draft tube for automatically relieving the chambered structure of accumulated water. 70
